Patented Oct. 23, 1973

228,755

COMBINED SAMPLER AND AUTOMATED CHEMISTRY APPARATUS

Henry E. Amar, Bronxville, N.Y., Herman G. Diebler,
North Haledon, N.J., and Jack Isreeli, Mamaroneck,
George Payne, Bedford Hills, and William J. Smythe,
Tarrytown, N.Y., assignors to Technicon Instruments
Corporation, Tarrytown, N.Y.

Filed June 9, 1972, Ser. No. 261,561

Term of patent 14 years

Int. Cl. D24—01

U.S. Cl. D16—2 C

FIG. 1

FIG. 2

FIG. 3

FIG. 4

FIG. 5

FIG. 1 is a front perspective view of combined sampler and automated chemistry apparatus showing our new design;

FIG. 2 is a front elevational view of the apparatus shown in FIG. 1;

FIG. 3 is a top plan view of the apparatus;

FIG. 4 is an elevational view of the side of the apparatus not seen in FIG. 1; and

FIG. 5 is a rear elevational view of the apparatus. We claim:

The ornamental design for a combined sampler and automated chemistry apparatus, substantially as illustrated.
